CLOTHES WRINGER

Lilith M. Palo, Sault Ste. Marie, Mich.

Application November 22, 1949, Serial No. 128,871

6 Claims. (Cl. 68—267)

1

This invention relates to clothes wringers and more particularly to a power operated clothes wringer which may be mounted on a washing machine, if desired, and driven by the mechanism of the machine.

It is among the objects of the invention to provide an improved clothes wringer which will operate positively and effectively to take in wet clothes, force all excess water out of the clothes and discharge the clothes without any fouling of the clothes in the wringer or wrapping of the clothes around any part of the wringer in the manner in which wet clothes frequently wrap around the rollers of existing roller type wringers, which is effective to compress the wet clothes over a large area at the same time to effectively squeeze the excess water from the clothes, and which is simple and durable in construction, economical to manufacture, and easy to use.

Other objects and advantages will become apparent from a consideration of the following description and the appended claims in conjunction with the accompanying drawings, wherein:

Figure 1 is a side elevation of a clothes wringer illustrative of the invention;

Figure 2 is a top plan view of the clothes wringer illustrated in Figure 1;

Figure 3 is an end view of the left hand end of the clothes wringer as illustrated in Figures 1 and 2;

Figure 4 is a transverse cross section on the line 4—4 of Figure 1;

Figure 5 is an end elevation of the right hand end of the clothes wringer as illustrated in Figures 1 and 2;

Figure 6 is a longitudinal cross section on the line 6—6 of Figure 1;

Figure 7 is a perspective view of a fragmentary view of a fragmentary portion of one component of the wringer illustrating structural details of such component; and

Figure 8 is a perspective view of a fragmentary portion of one component of the wringer illustrating structural details of such component; and

Figure 9 is a perspective view of a retaining cleat constituting an operative component of the device.

With continued reference to the drawings, the improved clothes wringer comprises, in general, a generally rectangular frame 10, a first set of rollers including the rollers 11, 12 and 13 extending longitudinally of the frame and journaled therein, a second set of rollers including the rollers 14, 15 and 16 also extending longitudinally of the frame and journaled therein, the rollers being

2

so located that each roller of one set is opposed to a corresponding roller of the other set and the six rollers of the two sets constitute three pairs of mutually opposed rollers, roller journaling means as designated at 17 for the end rollers 11, 13, 14 and 16 and as designated at 18 for the intermediate roller 12, a flexible band 19 trained over the rollers of the first set, a similar flexible band 20 trained over the rollers of the second set and having a portion between the two sets of rollers juxtaposed against a similar portion of the band 19, a drive shaft 21 journaled in the frame and chain and sprocket means 22 drivingly connecting the drive shaft to the end rollers of one of the sets of rollers.

The frame 10 comprises two elongated, rectangular end plates 25 and 26. The plate 25 has perpendicularly disposed flanges 27 and 28 extending respectively along its longitudinal edges 20 and the end plate 26 has similar flanges 29 and 30. In the assembled frame the flanges of the two end plates extend outwardly at the respectively opposite ends of the frame. Two top frame members 31 and 32 in the form of elongated bars 25 are secured to the top flanges 27 and 29 of the two end plates with the bar 31 at one end and the bar 32 at the opposite end of the end plates. The bars 31 and 32 extend beyond the end plate 25 at the side of this end plate opposite the end plate 26 and an outwardly arched cross member 33 connects the ends of the bars 31 and 32 extending beyond the end plate 25. Two similar bars 34 and 35 are secured to the flanges 28 and 30 of the end plates at the respectively opposite ends 30 of these flanges and the bars 34 and 35 extend beyond the end plate 25 and are connected at their ends extending beyond the end plate 25 by an outwardly bowed or arched cross member 36. A member 37 is connected at its respectively opposite ends to the cross members 33 and 36 at the mid-length locations of these cross members and is provided adjacent the cross member 36 with an aperture providing a bearing for the drive shaft 21.

The end plates 25 and 26 are substantially parallel to each other and are spaced apart a distance corresponding to the length of power operated clothes wringers now in use.

The rollers 11, 12 and 13 have shafts 40, 41 and 42 extending coaxially therethrough and the end plates 25 and 26 are provided with elongated apertures as indicated at 38 through which the corresponding ends of these shafts extend so that the rollers 11, 12 and 13 are disposed adjacent the

top flanges of the end members and in uniformly spaced apart relationship in the frame.

The rollers 14, 15 and 16 are provided respectively with longitudinally extending, coaxial shafts 43, 44 and 45 and the end plates 25 and 26 are provided with apertures as indicated at 38 through which these shafts extend at their correspondingly opposite ends, the apertures for the shafts 43 and 45 being elongated transversely of the end plates while the apertures for the shaft 44 are circular in shape to provide bearings for this shaft.

Each of the end plate flanges 27, 28, 29 and 30 is provided with apertures as indicated at 39 which apertures are in alignment with the corresponding roller axles or shafts extending through the corresponding apertures in the end plates and eye bolts 46, 47, 48 and 49 rotatably receive in the eyes thereof the ends of the shafts 40, 42, 43 and 45 respectively projecting outwardly of the end plate 26. These eye bolts extend through corresponding apertures 39 in the flanges 29 and 30 of the end plate 26, as is particularly illustrated in Figure 5, and coiled compression springs 50, 51, 52 and 53 respectively surround the bolts 46, 47, 48 and 49 between the bolt eyes and the corresponding flanges 29 and 30, these springs resiliently urging the rollers 11 and 14 and the rollers 13 and 16 together at the corresponding ends of these rollers. An eye bolt 54 rotatably receives in its eye the end of shaft 41 extending beyond the end plate 26 and this bolt is received in the screw threaded bore of a thumb nut 55 which bears on the flange 29. A compression spring 56 surrounds the bolt 54 between the eye of the bolt and the flange 29 and the force of this spring on the corresponding end of the shaft 41 is adjustable by rotation of the thumb nut 55. The end of the shaft 44 extending through the end plate 26 is journaled in the round aperture 57 in the end plate.

The ends of the shafts 40, 42, 43 and 45 extending through the end plate 25 are journaled respectively in the eyes of eye bolts 60, 61, 62 and 63 which eye bolts extend through corresponding apertures in the flanges 27 and 28, and compression springs 64, 65, 66 and 67 respectively surround these bolts between the eyes of the bolts and the corresponding flanges to urge the ends of the shafts or axles of opposed rollers toward each other. The end of the shaft 41 extending through the end plate 25 may be journaled in the eye of an eye bolt threaded into a thumb nut 68 to provide for this end of the shaft 41 a bearing support similar to that illustrated in Figure 5.

The drive shaft 21 may be an extension of the shaft 44 of the roller 15 and may be journaled in a circular aperture in the end plate 25 and in an aperture in the frame member 37, as explained above.

A chain sprocket 70 is secured on the shaft 43 at the end of this shaft extending beyond the end plate 25 and a chain sprocket 71 is secured on the corresponding end of the shaft 45. Two sprockets or a double sprocket are secured on the drive shaft 21 and drive chains 72 and 73 respectively trained around the sprockets 70 and 71 and a corresponding drive shaft sprocket drivingly connect the drive shaft to the outside rollers 14 and 16 so that all three of the rollers 14, 15 and 16 will be driven when the drive shaft 21 is rotated.

The drive shaft 21 may be drivingly connected to the wringer operating mechanism of a wash-

ing machine on which the wringer is mounted or may be driven by other suitable power or manually operated means as may be desired.

The rollers 11 to 16, inclusive, are preferably made of rubber or some similar material and each roller has thereon three lug wheels, as indicated at 74, 75 and 76 in Figure 6. The lug wheels 74 and 76 are located near the respectively opposite ends of the roller and the lug wheel 75 is mounted adjacent the mid-length location of the roller and these lug wheels engage the corresponding bands 19 and 20 to insure movement of the bands with rotation of the rollers without slippage of the rollers in the bands.

The two flexible bands 19 and 20 may be identical in construction and a description of only one is considered necessary for the purposes of the present disclosure, the band 19 having been selected for detail illustration and description.

This band comprises a plurality of flat, elongated metal plates of rectangular shape disposed in edge to edge relationship with each plate connected to its adjacent plate by a hinged structure comprising spaced apart apertured tongues 77 projecting from one edge of each plate and received in corresponding notches in the contiguous edge of the adjacent plate and suitable hinge pins 78 extending through the plates and tongues to pivotally secure adjacent plates together in the manner illustrated in Figure 8 for the two plates 79. Near their opposite ends and at their mid-length locations the plates 79 are provided with apertures 80 in which the teeth of the lug wheels 74, 75 and 76 engage and the link plates constitute a continuous band or belt, one such belt being trained around the three rollers 11, 12 and 13 of the first set of rollers and the other band being trained around the three rollers 14, 15 and 16 of the second set.

A series of uniformly spaced apart lugs 81 is secured to each plate 79 so that the series of lugs extends longitudinally of the plate substantially along the mid-width location thereof. These lugs may be secured to the plates by reduced extensions on the lugs extending through apertures 82 in the plates and riveted over, as indicated at 83 in Figure 7. Each lug 81 has at one end a bottom or base flange 84 bearing on the outer surface of the corresponding plate 79 and has at its opposite end an enlarged head or bead 85 connected to the base flange 84 by a thin web 86.

Elongated blocks 87 of suitable resilient material, such as vulcanized rubber, are secured on the plates by the lugs 81. These blocks 87 have recesses therein receiving the spaced apart lugs 81 and the blocks extend longitudinally of the plates 79 respectively and are preferably of square or rectangular cross sectional shape. These blocks have a width substantially equal to the width of the plates 79 so that in the straight portions of the bands the blocks are disposed in side by side contacting relationship, as illustrated in Figure 4, and provide at their outer faces a substantially continuous surface for each such band portion and the blocks are of such a thickness that the outer faces of the blocks of the two juxtaposed portions of the bands 19 and 20 between the first and second sets of rollers are in contact, as also illustrated in Figure 4, when the wringer is empty.

When the bands pass around the outer sides of the side rollers the adjacent blocks 87 are separated and move relative to any material

passing through the wringer. This slight separation of the outer faces of the blocks at each side of the wringer greatly facilitates the operation of the wringer providing a positive feed so that wet clothes are drawn into the wringer without material resistance and so that the clothes are discharged from the wringer without any appreciable tendency to follow the bands around the outside rollers at the discharge side of the wringer. This last operation is caused by the loosening effect occasioned by the separation of the blocks freeing the blocks from the clothes against which the blocks have been compressed during the passage of the clothes through the wringer between the juxtaposed portions of the two flexible bands. Also, since the use of the bands greatly increases the area of the wringer in compressive contact with the clothes, the excess water is more effectively squeezed out of the clothes as the clothes pass through the 20 wringer.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A clothes wringer comprising a generally rectangular frame, at least two pairs of opposed rollers mounted in said frame, journal means for said rollers carried by said frame and resiliently forcing the two rollers of each pair of opposed rollers together, two jointed bands trained over said rollers and carried thereby so that each band encompasses one roller of each pair of opposed rollers and said bands are juxtaposed along adjacent portions thereof and resiliently forced together by the roller journal means, and means carried by said frame and connected to the rollers within at least one of said bands for driving such rollers.

2. A clothes wringer comprising a generally rectangular frame, at least two pairs of opposed rollers mounted in said frame, journal means for said rollers carried by said frame and resiliently forcing the two rollers of each pair of opposed rollers together, two jointed bands trained over said rollers and carried thereby so that each band encompasses one roller of each pair of opposed rollers and said bands are juxtaposed along adjacent portions thereof and resiliently forced together by the roller journal means, means carried by said frame and connected to the rollers within at least one of said bands for driving such rollers, said frame comprising two end plates of elongated rectangular shape having perpendicularly disposed flanges along the longitudinal edges thereof and having transversely elongated apertures therein, elongated bars secured at their ends to the flanges of said end plates respectively at the respectively opposite ends of such flanges to hold said end plates in spaced apart position substantially parallel to each other, and each of said rollers having an elongated coaxial shaft extending at its ends through the corresponding apertures in said end plates, said flanges having apertures therein and said journal means for said rollers comprising eye bolts extending through corresponding apertures in said flanges and rotatably receiving in the eyes thereof end 75

portions of corresponding roller shafts extending through the apertures in said end plates, and coil compression springs respectively surrounding said eye bolts between the eyes thereof and the corresponding end plate flanges.

3. A clothes wringer comprising a generally rectangular frame, at least two pairs of opposed rollers mounted in said frame, journal means for said rollers carried by said frame and resiliently forcing the two rollers of each pair of opposed rollers together, two jointed bands trained over said rollers so that each band encompasses one roller of each pair of opposed rollers and said bands are juxtaposed along adjacent portions thereof and resiliently forced together by the roller journal means, means carried by said frame and connected to the rollers within at least one of said bands for driving such rollers, said frame comprising two end plates of elongated rectangular shape having perpendicularly disposed flanges along the longitudinal edges thereof and having transversely elongated apertures therein, elongated bars secured at their ends to the flanges of said end plates respectively at the respectively opposite ends of such flanges to hold said end plates in spaced apart position substantially parallel to each other, and each of said rollers having an elongated coaxial shaft extending at its ends through corresponding apertures in said end plates, said flanges having apertures therein and said journal means for said rollers comprising eye bolts extending through the corresponding apertures in said flanges and rotatably receiving in the eyes thereof end portions of corresponding roller shafts extending through the apertures in said end plates, and coil compression springs respectively surrounding said eye bolts between the eyes thereof and the corresponding end plate flanges.

4. A clothes wringer comprising a generally rectangular frame, at least two pairs of opposed rollers mounted in said frame, journal means for said rollers carried by said frame and resiliently forcing the two rollers of each pair of opposed rollers together, two jointed bands trained over said rollers so that each band encompasses one roller of each pair of opposed rollers and said bands are juxtaposed along adjacent portions thereof and resiliently forced together by the roller journal means, means carried by said frame and connected to the rollers within at least one of said bands for driving such rollers, said frame comprising two end plates of elongated rectangular shape having perpendicularly disposed flanges along the longitudinal edges thereof and having transversely elongated apertures therein, elongated bars secured at their ends to the flanges of said end plates respectively at the respectively opposite ends of such flanges to hold said end plates in spaced apart position substantially parallel to each other, and each of said rollers having an elongated coaxial shaft extending at its ends through corresponding apertures in said end plates, said flanges having apertures therein and said journal means for said rollers comprising eye bolts extending through the corresponding apertures in said flanges and rotatably receiving in the eyes thereof end 70

receiving in the eyes thereof end portions of the corresponding roller shafts extending through the apertures in said end plates, coil compression springs respectively surrounding said eye bolts between the eyes thereof and the corresponding end plate flanges, and each of said jointed bands comprising a series of flat plates of elongated rectangular shape hinged together at their contiguous edges to constitute a continuous band, lugs secured on each plate and projecting outwardly therefrom, and an elongated block of resilient material secured on each plate by the corresponding lugs, said plates having apertures therein, and lug wheels on said rollers engaging in the apertures in said plates to preclude slippage between said rollers and said bands.

5. In a clothes wringer including a frame, at least two spaced apart pairs of rollers disposed within said frame with the rollers of each pair mutually opposed, means journaling said rollers in said frame and resiliently urging the opposed rollers of each pair together, and means driving at least one of said rollers, jointed bands trained over said rollers so that each band encompasses one roller of each pair of rollers and said bands are juxtaposed along adjacent portions thereof between said pairs of rollers, each of said bands comprising a plurality of flat plates of elongated rectangular shape and substantially rigid character disposed in side-by-side relationship and pivotally interconnected at their adjoining edges to constitute an endless belt having a width substantially equal to the length of said rollers, a body of resilient material of rectangular cross-sectional shape overlying the outer surface of each plate, and having a length and breadth substantially the same as the length and breadth of the plates, and rigid lugs secured to each plate at spaced apart locations therealong and embedded in the corresponding body of resilient material to secure said bodies of resilient material to the corresponding plates, said plates having a width providing for the free passage of the belts constituted thereby around said rollers and each having apertures disposed one near each end thereof, and said rollers each having sprocket wheel formations disposed one near each end thereof and engaging in the apertures in said plates.

6. In a clothes wringer including a frame, at least two spaced apart pairs of rollers disposed within said frame with the rollers of each pair mutually opposed, means journaling said rollers in said frame and resiliently urging the opposed

10
15

rollers of each pair together, and means driving at least one of said rollers, jointed bands trained over said rollers so that each band encompasses one roller of each pair of rollers and said bands are juxtaposed along adjacent portions thereof between said pairs of rollers, each of said bands comprising a plurality of flat plates of elongated rectangular shape and substantially rigid character disposed in side-by-side relationship and pivotally interconnected at their adjoining edges to constitute an endless belt having a width substantially equal to the length of said rollers, a body of resilient material of rectangular cross-sectional shape overlying the outer surface of each plate, and having a length and breadth substantially the same as the length and breadth of the plates, and rigid lugs secured to each plate at spaced apart locations therealong and embedded in the corresponding body of resilient material to secure said bodies of resilient material to the corresponding plates, said plates having a width providing for the free passage of the belts constituted thereby around said rollers and each having apertures disposed one near each end thereof, and said rollers each having sprocket wheel formations disposed one near each end thereof and engaging in the apertures in said plates.
